D. MARINSKY

CLOSURE DEVICE

1,887,940

Filed March 3, 1930

UNITED STATES PATENT OFFICE

DAVIS MARINSKY, OF NEW YORK, N. Y.

CLOSURE DEVICE

Application filed March 3, 1930. Serial No. 432,697.

This invention relates to closure devices adapted for use in connection with articles of various kinds and classes such for example as tobacco pouches, pocketbooks, cases, bags and the like; and the object of the invention is to provide the open end of the particular article in question with a frame involving two sets of tensional link units arranged in opposed relation, the adjacent ends of which are pivoted together whereby the opening in an article may be normally maintained closed under the tension of the link units of the device and separated under applied pressure, or whereby the tendency of the closure device will be to normally maintain the article in open position under the tension of said links, means being provided to retain the same in closed position against the action of said tensional means; a further object being to provide a closure device of the class specified which will provide a neat and finished closure for articles of various kinds and classes, maintaining a substantially air-tight joint at the open end of the article when the device is in closed position; a further object being to provide a closure of the class specified which will operate to quickly open and close the article to which it is applied, accomplishing this result with the least amount of effort and loss of time; a further object being to provide a closure device which may be manufactured at a very reasonable price permitting its application to articles of various kinds and classes and reducing the manufacturing cost and ultimate retail price of the article and in many cases, producing a better product; and with these and other objects in view, the invention consists in a closure device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

50 Fig. 1 is a perspective view of a tobacco

pouch illustrating one of my improved devices attached thereto.

Fig. 2 is a view similar to Fig. 1 illustrating the method of opening the device, and showing the same in open position.

55 Fig. 3 is a partial section on the line 3—3 of Fig. 1 on an enlarged scale.

Fig. 4 is a sectional view through the joint of one of the link units which I employ.

Fig. 5 is a section on the line 5—5 of Fig. 4. 60

Fig. 6 is a section on the line 6—6 of Fig. 1.

Fig. 7 is a plan and sectional view of a modified form of device which I employ.

Fig. 8 is a perspective detail view of a part of one side and corner portion of the tobacco 65 pouch shown in the several figures.

Fig. 9 is a view similar to Fig. 4 showing a modification; and,

Fig. 10 is a partial section on the line 10—10 of Fig. 9.

70 It will be understood that my invention may be applicable to articles of various kinds and classes such for example as tobacco pouches, pocketbooks, cases, bags and the like.

To illustrate one use of the invention, I 75 have shown the device applied to one of these articles, namely a tobacco pouch; and the closure device herein disclosed constitutes an improvement on the resilient link body forming the subject matter of a prior U. S. patent 80 granted to me December 17, 1929, No. 1,739,976.

In the drawing, 10 represents a tobacco pouch of more or less conventional form and composed of any suitable material, the upper 85 edge of the pouch being folded inwardly and stitched as seen at 11 to form a chamber 12 within the fold and extending from one side seam 13 to the other. It is preferred that apertures 14 be formed on the inturned faces 90 of the pouch adjacent the side seams thereof as indicated in Fig. 8 of the drawing, other apertures 15 being arranged on the outer face of the pouch centrally of the opposite walls thereof, the apertures 14 and 15 communicating with the chambers 12. This structure facilitates the attachment of my improved closure device to the pouch, as later described.

100 In the construction shown in Figs. 1 to 6

inclusive my improved closure device consists of two spring link units 16—16 α both of which are of similar construction and the description of one unit will suffice for both. 5 Each unit consists of two rods 17 and 18 which may be tubular in form or have tubular ends 17 α —18 α , note Fig. 3, in which the projecting ends 19 and 20 of a coil spring 21 are adapted to be placed. The winding of 10 the spring and the extension of the ends 19 and 20 is such that the rods 17 and 18 of the respective links are normally held in abutting relation under the tension of the springs 21. 15 Arranged on the springs to form a finish therefor as well as a reinforcing member and stop is a cap 22 one side wall of which is cut out as shown at 22 α to limit the separation of the rods 17 and 18. The cap carries a central 20 rivet pin 23 which is adapted to be riveted to a plate 24 arranged at the lower face of the cap after the spring has been mounted on the pin and arranged within said cap. This structure is clearly shown in Figs. 3, 4, and 5 25 of the drawing. The ends of the rods 17 and 18 are fashioned to form outwardly extending lugs 25 which are apertured to receive pivot pins 26 and 27. The pin 26 has a reduced neck 28 adjacent its upper end where- 30 as the pin 27 is apertured to receive a catch plate 29 adapted to be snapped onto the pin 26 in securing the separate parts of the device together.

As seen in the drawing, the adjacent ends 35 of the rods 17—18 of each unit 16—16 α are pivoted together by the pins 26 and 27 and in assembling a complete device, each link unit is first attached to the pouch by passing the ends of the rods 17 and 18 through the 40 apertures 14, thus through the chambers 12 and until the projections 25 extend out through the apertures 15 centrally of the pouch. After both units are mounted in position, the pins 26 and 27 are secured in position, thus completing the assemblage of the 45 complete device. The rounded caps which, by the way, may be ornamented in any desired manner, produce a neat and finished appearance at the top side corner portions of 50 the pouch as clearly seen in Figs. 1 and 2 of the drawing.

In the use of the device, it will be understood that the open end of the pouch is normally maintained in closed position by the 55 tension of the springs 21 at the pivoted ends of the respective units, adjacent surfaces of the rods 17 and 18 being held in abutting relation under this tension, with of course, the fabric of the pouch between said rods, thus sealing the open end of the pouch.

When it is desired to open the pouch and after the catch 29 has been released, pressure is applied to the pivoted ends of the links in the manner indicated in Fig. 2 of the drawing, the thumb of the hand engaging the piv-

oted end of one link unit and a finger of the hand engaging the pivoted end of the other unit; and by moving said pivoted ends together in a grip-like action, the central portion of the pouch or the side walls thereof 70 will extend laterally and in opposite directions in the manner shown in Fig. 2 of the drawing, to give access to the pouch in the operation of filling a pipe. It will be understood that the release of the hand pressure 75 will automatically operate to close the open end of the pouch and to insure maintaining the pouch in this position the catch device 29 may be employed, but the use of the latter is 80 not absolutely necessary.

In Fig. 7 of the drawing, I have shown a slight modification which differentiates from the structure shown in Figs. 1 to 6 inclusive, simply in that the ends 19 α and 20 α of the coil spring 21 α in each spring-link unit, instead of being crossed as clearly seen in Fig. 3, are extended directly from the coil to normally maintain the rods of the link units in separated relation with respect to each other, the normal position of the parts being shown 85 in Fig. 7 of the drawing. With this construction, the pouch or other article is closed by applying pressure to opposite and normally separated walls of the article to bring the same into abutting relation, after which the catch device is moved into position to maintain the device closed, and the instant that the catch is released, the article will be automatically opened. In other words, this 90 structure simply reverses the process disclosed in Fig. 2 of the drawing and may be found to be practical and advantageous in articles of various kinds and classes.

As hereinbefore stated, my invention may be used in connection with many types of 100 articles requiring closure means or device and will find its usefulness as a substitute for what are known as slide fasteners having interengaging coupling elements. It will also be apparent that the use of the springs is not 105 absolutely essential, as the spring ends of the rods may constitute pivots.

In Figs. 9 and 10, I have shown a slight modification wherein the rods 30 and 31 of each link unit have at the spring ends thereof 110 relatively flat plates 30 α and 31 α which overlie and are apertured to receive the pivot and rivet pin 32 on the cap 33 which encloses the coil spring 34. The ends of the spring 34 115 are adapted to be placed in the tubular bores 35 and 36 of the rods 30 and 31, and with this construction, it is essential that the ends of the springs be secured to the rods as would be the case with the structure shown in the 120 other figures. With the construction shown in Figs. 9 and 10, the rods 30 and 31 are directly pivoted together and when the cost 125 of the device is not an item, this would be the preferred structure; and when the spring 130

is not necessary or desirable, this structure would be employed.

While certain structural details of the device are shown in illustrating one method of carrying the invention into effect, it will be apparent that I am not necessarily limited to the specific structures herein shown and described nor to the use herein illustrated and various changes in and modifications of the invention herein disclosed may be made within the scope of the appended claims without departing from the spirit of my invention or sacrificing its advantages.

Having fully disclosed my invention, what I claim as new and desire to secure by Letters Patent, is:

1. A closure device of the class described comprising two similar spring link units arranged in opposed relation, each unit comprising a pair of straight rods, means involving a coil spring for pivotally coupling one end of each pair of rods, said springs having end portions engaging said rods to support the same in predetermined relation with respect to each other and to dispose the coils of said springs in spaced relation to the ends of said rods, and the other ends of the rods of the separate units being pivotally coupled to form a frame having the spring pivots disposed at opposed ends of the frame.

2. A closure device of the class described comprising two similar spring link units arranged in opposed relation, each unit comprising a pair of straight rods, means involving a coil spring for pivotally coupling one end of each pair of rods, said springs having end portions engaging said rods to support the same in predetermined relation with respect to each other and to dispose the coils of said springs in spaced relation to the ends of said rods, the other ends of the rods of the separate units being pivotally coupled to form a frame having the spring pivots disposed at opposed ends of the frame, and said first named means involving cup-shaped caps disposed outwardly of said rods and enclosing the springs of each unit.

3. A closure device of the class described comprising two similar spring link units arranged in opposed relation, each unit comprising a pair of straight rods, means involving a coil spring for pivotally coupling one end of each pair of rods, said springs having end portions engaging said rods to support the same in predetermined relation with respect to each other, the other ends of the rods of the separate units being pivotally coupled to form a frame having the spring pivots disposed at opposed ends of the frame, said first named means involving cup-shaped caps enclosing the springs of each unit, and means on said caps for limiting the movement of the rods of each unit with respect to each other.

4. An article of manufacture comprising a

container composed of flexible material, opposed walls of the container having at the open end thereof chambers extending longitudinally of said walls and forming the free edges thereof, said chambers opening into the container at each end thereof and the upper edge of the fabric forming said chambers being provided centrally with apertures, a closure frame for said container comprising two substantially similar V-shaped frame units, each unit consisting of a pair of rods pivotally coupled at one end and including springs on said pivot cooperating with the rods to support them normally in predetermined position with respect to each other, the free ends of the rods in each pair being inserted into the chambers through the openings at each end of the container and the free ends of the rods of each unit being pivotally coupled together where said apertures are located, and said pivots including knobs extending upwardly through said apertures and projecting above the top of the container.

5. An article of manufacture comprising a container composed of flexible material, opposed walls of the container having at the open end thereof chambers extending longitudinally of said walls and forming the free edges thereof, said chambers opening into the container at each end thereof and the upper edge of the fabric forming said chambers being provided centrally with apertures, a closure frame for said container comprising two substantially similar V-shaped frame units, each unit consisting of a pair of rods pivotally coupled at one end and including springs on said pivot cooperating with the rods to support them normally in predetermined position with respect to each other, the free ends of the rods in each pair being inserted into the chambers through the openings at each end of the container and the free ends of the rods of each unit being pivotally coupled together where said apertures are located, said pivots including knobs extending upwardly through said apertures and projecting above the top of the container, and interengaging means on said knobs for securing the frame together in closed position.

6. An article of manufacture comprising a container composed of flexible material, opposed walls of the container having at the open end thereof chambers extending longitudinally of said walls and forming the free edges thereof, said chambers opening into the container at each end thereof and the upper edge of the fabric forming said chambers being provided centrally with apertures, a closure frame for said container comprising two substantially similar V-shaped frame units, each unit consisting of a pair of rods pivotally coupled at one end and including springs on said pivot cooperating with the rods to support them normally in predetermined position.

mined position with respect to each other, the free ends of the rods in each pair being inserted into the chambers through the openings at each end of the container and the free ends of the rods of each unit being pivotally coupled together where said apertures are located, said pivots including knobs extending upwardly through said apertures and projecting above the top of the container, interengaging means on said knobs for securing the frame together in closed position, and the tension of the springs of said frame units being such as to automatically open the container in releasing said securing means.

15 7. An article of manufacture comprising a container composed of flexible material, opposed walls of the container having at the open end thereof chambers extending longitudinally of said walls and forming the free edges thereof, said chambers opening into the container at each end thereof and the upper edge of the fabric forming said chambers being provided centrally with apertures, a closure frame for said container comprising two substantially similar V-shaped frame units, each unit consisting of a pair of rods pivotally coupled at one end and including springs on said pivot cooperating with the rods to support them normally in predetermined position with respect to each other, the free ends of the rods in each pair being inserted into the chambers through the openings at each end of the container and the free ends of the rods of each unit being pivotally coupled together where said apertures are located, said pivots including knobs extending upwardly through said apertures and projecting above the top of the container, interengaging means on said knobs for securing the frame together in closed position, the tension of the springs of said frame units being such as to automatically open to the container in releasing said securing means, and said first named pivots including cup-shaped caps exposed through the top of the container at the ends thereof and concealing the springs of said pivots.

30 35 40 45 50

In testimony that I claim the foregoing as my invention I have signed my name this 28th day of February 1930.

DAVIS MARINSKY.
